VARIABLE LENGTH BOLT LEVER

Richard H. Colby, South Hadley, Mass., assignor to the United States of America as represented by the Secretary of the Army

Application November 17, 1955, Serial No. 547,591

4 Claims. (Cl. 42—16)

(Granted under Title 35, U. S. Code (1952), sec. 266)

The invention described herein may be manufactured and used by or for the Government for governmental purposes without the payment of any royalty thereon.

My invention relates to a bolt-operated gun and more particularly to such a gun having a telescoping device for actuating the bolt thereof.

A conventional machine gun includes a receiver, and a recoil unit biased to a battery position therein and provided with a barrel for battery position discharge of cartridges therein. The recoil unit is disposed for reciprocal operation responsive to the discharge and provided with an arm pivoted on the recoil unit and a slideable bolt for gripping the cases of the cartridges having a slideway for engaging the arm at the free end thereof. The arm is disposed for engagement with a receiver cam for synchronous operation of the bolt to extract the cases from the barrel responsive to the rearward portion of the reciprocal operation. An ejector stop in the feed portion of the receiver engages the cases in the rearward strokes of the bolt to rotate the cases out of the bolt, and the cases pass through an ejection port in the bottom of the receiver.

The distance between the stop and the port is substantially two and one-half inches, and the cases are slightly more than two inches long allowing the cases to rotate inside the gun. Because of the unchecked rotation within the gun, cases have been known to strike the arm, and on the forward stroke of the bolt to become jammed in the receiver and cause malfunction of the gun.

It is an object of my invention to provide such a gun with a receiver of minimum height to curtail rotation of the cases within the gun.

Another object of my invention is to limit the space between the ejector stop and the ejection port to less than the length of a cartridge case for projection of the cases from the gun during the rotation.

A further object of my invention is to provide such a gun with a telescoping arm for actuating the bolt of the gun to decrease the height of the receiver for decrease in the displacement between the stop and the ejection port of the gun.

A still further object of my invention is to provide such a gun having a minimum height for minimum silhouette of the gun.

Other aims and objects of my invention will appear in the following explanation thereof.

In carrying out my invention, the crank for actuating the bolt is provided with an arm pinned to the bolt and provided with roller operating telescoping sections to permit a decrease of substantially one inch in depth, respectively, of the recoil unit and the receiver.

The space between the ejection port and the stop is limited to less than the length of a cartridge case to ensure projection of the cases through the ejection port in the first ninety degrees of revolution of the cases from the stop. The cases either pass directly through the ejection port or rebound from engagement with the bottom of the receiver to leave the gun. Interference with the

arm in this construction would tend to propel the case from the gun in the forward stroke of the bolt.

The net decrease in dimensions of the receiver, the recoil unit, and the bolt results in a significant decrease in the weight and silhouette of the gun, both of which results are highly desirable in the art of guns.

For a more complete understanding of my invention reference is directed to the following description and the accompanying drawing in which:

10 Fig. 1 is an elevation partly cut away of a gun incorporating an embodiment of my invention with the bolt in battery position;

Fig. 2 is a view similar to Fig. 1 with the bolt in retracted position; and

15 Fig. 3 is a view similar to Figs. 1 and 2 with the crank in the midposition thereof.

Accordingly, a weapon 12 having a receiver 14 includes a recoil unit 16 biased to a battery position in the receiver and secured to a barrel 18. A bolt 20 includes a laterally 20 slideable breechblock 21 to retain a cartridge 22 in barrel 18 for battery position discharge of the cartridge. Cartridges 22 are slideable to a feeder 15 adjacent recoil unit 16 and the recoil unit is slideable on rails 17 for recoil reciprocation responsive to the discharge. A crank 24 pivoted at 26 in the recoil unit is provided with rollers 25 engageable with a receiver cam 27 to actuate bolt 20 in reciprocal stroke operation in slots 29 responsive to the reciprocation.

Crank 24 includes an arm with a hollow hub portion 30 28 and an extension 30 is provided with rollers 32 engageable in portion 28 and pivotably connected at 34 to bolt 20 to permit extension 30 to slide in and out of portion 28 during the reciprocal stroke operation.

Bolt 20 is constructed to grip case 36 of cartridge 22 35 and an ejector stop 38 is disposed on receiver 14 for rotation of cases 36 from bolt 20 in the rearward strokes thereof to permit the cases to pass through an ejection port 40 in the bottom of receiver 14. The length of cartridge cases 36 is slightly more than two inches and the distance between stop 38 and port 40 is substantially 40 one and one-half inches. As shown in Fig. 2, the front ends of cases 36 project through port 40 during rotation from stop 38 and the cases are ejected from gun 12 even if the front ends impinge on the bottom of receiver 14. 45 Arm 28 tends to aid ejection of cases 36 in the forward stroke of bolt 20.

Although a particular embodiment of the invention has been described in detail herein, it is evident that many variations may be devised within the spirit and scope thereof and the following claims are intended to include such variations.

I claim:

1. In a gun including a receiver with a cartridge ejection port in the bottom thereof, a cam provided in the receiver, a feeder on the receiver for inclosing cartridges, a recoil unit slidably disposed in the receiver for reciprocal operation, a barrel, and a bolt in the recoil unit respectively disposed to chamber the cartridges and to retain the chambered cartridges in the barrel in the battery position for discharge thereof, a crank device for operating the bolt comprising an arm provided on the recoil unit for engagement with the cam, and an extension secured to the bolt, said extension being disposed in said arm for telescopic operation during the reciprocal operation of the recoil unit for maintaining contiguous relation 60 of the feeder and the recoil unit.

2. A device as in claim 1 wherein said extension is provided with journaled rollers longitudinally spaced and said arm is provided with a hollow portion engageable by said rollers for telescopic operation.

3. A gun comprising a receiver with a cartridge ejection port in the bottom thereof, a cam provided in said

receiver, a feeder for inclosing cartridges disposed in said receiver, a recoil unit slidably disposed in said receiver for reciprocal operation, a barrel and a bolt disposed on said recoil unit respectively to chamber the cartridges and to retain the chambered cartridges in said barrel in the battery position for discharge thereof, and a crank pivoted on said recoil unit for engagement with said cam and provided with an extension secured to said bolt, said cam being disposed for reciprocal operation of said bolt during the reciprocal operation of said recoil unit and said extension being disposed for telescopic operation during the reciprocal operation for maintaining contiguous relation of said feeder and said recoil unit.

4. A gun as described in claim 3 with said receiver provided with a stop adjacent the path of said bolt to 15

engage the cases for rotation from said bolt during the rearward strokes of the recoil unit, the forward opening of said port being spaced at less than the length of spent cartridge cases from said stop for ensuring projection of the cases through said port in the first quarter of said rotation.
